5 Claims

ABSTRACT OF THE DISCLOSURE

A method of washing solid, more particularly textile articles, with an organic solvent, improved by adding an intensifier.

The intensifier is a primary or secondary amide of a dicarboxylic aliphatic acid or anhydride wherein one carbon atom in the chain connecting the two acid groups bears an alkyl or alkenyl radical containing at least six carbon atoms.

The method gives better whiteness and more particularly prevents the re-deposition of dirt.

The invention relates to an improvement to "dry" cleaning of textiles, i.e., the washing of textile fibres or articles with non-aqueous solvents. The invention relates more particularly to the use of a novel kind of adjuvants which improve cleaning and give more thorough bleaching or cleaning. The invention relates to the novel kind of dry-cleaning intensifiers and to baths containing the aforementioned adjuvants.

"Dry" cleaning is an activity which has recently become widely extended and which uses large tonnages of solvents. The solvents are mainly chlorinated hydrocarbons, more particularly perchloroethylene and trichloroethylene which, owing to their nonflammability and other advantageous properties, have become the main solvents used in this branch of industry. Whatever solvent is used, however, i.e. petrol, hexane or other aliphatic or benzene hydrocarbons, or chlorinated, chlorofluorinated or other solvents, the solvent does not usually produce adequate cleaning by itself; it is well known to add surface-active agents soluble in the given solvent to the cleaning bath. For example it has become conventional to add agents such as the following to the solvents: amine alkyl-aryl sulfonates, ethoxylated derivatives of aliphatic amines or alcohols, or alkyl-polyethoxy-phenols. In spite of the aforementioned additives, which are often accompanied by optical bleaching agents and bleaching agents, progress still needs to be made in the art of cleaning with solvents, since the results are not yet perfect; the degree of cleaning, or the whiteness of textile fibres or articles cleaned by the aforementioned method usually leaves something to be desired. It is therefore necessary to find agents which, when added to dry-cleaning baths, improve the aforementioned results; this is the problem which the invention proposes to solve.

The invention provides a novel kind of adjuvants for dry-cleaning baths which substantially improve the degree of cleaning compared with that obtained with conventional surface-active agents. In addition, the novel adjuvants are particularly effective when used together with conventional surfactants in the presence of a small proportion of water in the solvent; the resulting cleaning is much more thorough than could be obtained with either of the additives—i.e., the adjuvant according to the invention and the conventional agent—if used alone.

The intensifier according to the invention comprises one or more primary or secondary amides derived from an aliphatic diacid or anhydride, bearing an alkyl or alkenyl substituent, and an aliphatic polyamine, the number of

2

carbon atoms in the substituent being greater than in the polyamine.

The length of the chain of the hydrocarbon substituent is such that the intensifier is soluble in the given solvent; this means that the chain must usually contain at least 6 carbon atoms, preferably more than 12 C. In the case of chlorinated solvents, the best intensifiers are those in which the hydrocarbon substituent forms a chain of 18 to 200 carbon atoms, preferably 24 to 120 C.

- 10 The carboxylic acid entering into the composition of the primary amides or secondary amides (imides) according to the invention may have their two carboxylic groups in all positions from α - β to α - ω . Since, for economic reasons, the products used are mainly derived from C₃ to C₆ diacids (or anhydrides), i.e. from malonic to adipic acid, the carboxylic groups are at the two ends of a chain formed by 1 to 4 CH₂ and the alkyl or alkenyl substituents is attached to one of the carbon atoms in the chain. In addition, however, to the aforementioned acids—i.e. 15 malonic, succinic, glutaric and adipic acid—a number of others can be used as the base of the primary amides or imides according to the invention.

For example, the base can also comprise derivatives corresponding e.g. to pimelic, suberic, azelaic, sebacic acid, etc., i.e. heptane-, octane-, nonane- or decane-dioic acid respectively, bearing a long alkyl or alkenyl group on one of the carbon atoms connecting the two —COOH or —CO—O—CO groups.

In addition to the aforementioned α - ω diacids, the amide derivatives according to the invention can come from acids whose carboxyl groups are in positions other than the α - ω positions in their aliphatic chains. Suitable acids correspond e.g. to: 2,5-dicarboxyhexane; 1,4-dicarboxyhexane; 1,6 - dicarboxyoctane; 5,7 - dicarboxyundecane; 1,4-dicarboxydodecane; 1,8-dicarboxyoctadecane (a derivative of oleic acid), etc.

The polyamines from which the amide group of the intensifiers according to the invention is derived are preferably alkylene-polyamines but can if required comprise alcohol-amines, phenol-amines or aromatic amines, provided that they contain at least two atoms of aminated nitrogen per molecule. The following substances are preferred examples of the first group: ethylene-diamine; diethylene-triamine, triethylene-tetramine, tetraethylene-pentamine, pentaethylene-hexamine, pentamethylene-diamine, hexamethylene-diamine, tripropylene-tetramine, tetrapropylene-pentamine, etc., or polyalkylene-polyamines or mixtures of heavy polyalkylene polyamines obtained as residues in the manufacture of the aforementioned substances. Cyclic polyamines are also suitable, more particularly piperazine and derivative thereof substituted on the nitrogen atom by one or more alkyl groups, e.g. N-ethyl, N-methyl, N-isopropyl, N-methyl-(β -amino-ethyl)-piperazine etc. The alkyl groups of the aforementioned polyamines may also be branched.

The amides according to the invention may also be derived from other amines such as: alkyl- or dialkyl-amino-alkyl amines such as methyl-amino-, propylamine, dimethylamino-ethylamine, diethylamino-butylamine; aryl polyamines such as phenylene di- or tri-amine, triamino-toluene, triamino-triphenyl-methane, diamino-diphenol-amine, triamine-phenol, etc.; or alcohol-amines such as di-1,3-amino-2-propanol, 1,2-diamino-3-propanol, triaminohexanol etc.

In some cases, more particularly when the number of nitrogen atoms in the amine is relatively large, it may be advantageous to block all or some of the amine groups which have not been converted into amide, by substitution or an addition reaction. For example, depending on the particular embodiment of the invention, the primary or secondary amide in the intensifier contains nitrogen atoms

bearing hydrocarbyl radicals, inter alia aryl, more particularly alkyl radicals, acyl groups, aryl-sulphonic radicals, or alkoxy or polyoxyalkylene groups. Similarly, one or more of the amine groups can be blocked by adding a molecule of an organic, mineral or mixed acid.

The amine groups can be blocked before or during the preparation of the amide. Appropriate reagents, inter alia alkyl halides such as methyl, ethyl, propyl, butyl or amyl chloride or bromide, are described in American Pat. No. 2,638,450, which also cites some examples of polyalkylene-polyamines, e.g. N-alkylated polyamines. Of course, the aforementioned examples in no way limit the present invention.

The reagents can also be acids or acid anhydrides and halides such as acetic, propionic and butyric acid and anhydrides and chlorides thereof; other reagents are non-limitatively cited in American Pat. No. 2,568,876. Advantageously, aryl-sulphonic groups are fixed with sulphonic acids whose alkali metal salts are known surfactants and whose amine salts are used in conventional dry cleaning. For example, the following substances are suitable: arylsulphonic acids in which the aryl group is benzene, toluene, octyl-benzene, dodecyl-benzene, naphthalene, butyl naphthalene, n-naphthol, etc. Preferably the sulphonic group is in the para position of the alkyl group in benzene derivatives and in the α or β position in the naphthalenes. Alkylsulphonic acids such as octyl-, lauryl- or oleyl-sulphonic acid can also be used.

The alkoxy or poly-oxyalkylene groups can be fixed on all or some of the nitrogen atoms in the starting amine or the final amide by a conventional condensation reaction with an oxide of an olefin or a poly-oxyalkylene. Ethylene oxide and propylene oxide are the most common reagents but others can of course be used, e.g. the oxides of butenes, amylenes or hexenes.

The primary or secondary amides according to the invention can be on one or more of the amine groups of the starting polyamine. In other words, the number of mols of polyamine may vary with respect to the number of mols of diacid or anhydride; the ratio may vary for instance from 0.5 to 2 but is preferably between 0.5 and 1.

The following formula non-limitatively illustrates the composition of a series of homologous imides according to the invention:

The aforementioned imides come from the condensation of an anhydride

with a polyethylene-polyamine

in which R is an alkyl or alkenyl group preferably having between 18 and 120 carbon atoms in the chain, n is usually between 0 and 6; Z is a hydrogen atom or one of the aforementioned groups blocking the amine group, e.g. an alkyl, an acyl, a moiety of an alkyl- or arylsulphonic acid, or a polyoxyalkylene group; Q is a hydrogen atom or a blocking group similar to but not necessarily identical with Z, and the sum $(m+p)$ is usually between 2 and 7, since the amino chain need not be very long.

In the particular case where, for example, R is a straight polypropylene chain containing 13 propylene links, $n=2$; $Q=H$; $(m+p)=4$ and Z is paradodecyl-benzene-sulphonic acid radical; the product is a polypropenyl-glutaric

monoimide of tetraethylene pentamine in which the terminal, non-amido nitrogen atom is blocked in the form of dodecylbenzene sulphonates:

The aforementioned illustration relates to a monoimide, i.e. a secondary mono-amide, but a di-imide could of course also be used according to the invention; in the latter case the Z group is a second glutaric acid or anhydride radical (2 mole of diacid per mol of polyamine). In the special case of polypropenyl-glutarimide, therefore, the last-mentioned formula has the same configuration at 20 the right and at the left end.

Since the condensation of diacids or anhydrides with polyamines is well known, there is no need to describe it here; we shall merely mention that it is usually performed between 100° and 250° C. with elimination of the water formed, e.g. in the form of an azeotropic mixture with benzene or toluene. Condensations of the aforementioned kind are described inter alia in the U.S. patents cited hereinbefore. Similarly, an aliphatic chain can be fixed on to dicarboxylic acids by conventional methods; 30 for example the fixing of polyolefin chains onto diacids such as maleic, fumaric, itaconic or citraconic acid is described in U.S. Pat. No. 2,283,214. Since maleic anhydride is particularly plentiful in industry, succinimides, which are derived from this raw material, are among the 35 cheapest intensifiers according to the invention.

The novel adjuvants to dry-cleaning baths are compatible with all solvents commonly used in the art—i.e. chloro, fluoro- or chlorofluoro-hydrocarbons, more particularly aliphatic hydrocarbons, and specially trichloroethylene and perchloroethylene; benzene type hydrocarbons, inter alia benzene, toluene, xylenes and naphtha solvent, aliphatic hydrocarbons such as hexane, heptane, octane, mineral oil, gas oil and petroleum ether. Of course, one skilled in the art can choose the intensifier 45 which is most suitable for a particular bath.

The bath, besides containing one or more intensifiers according to the invention, can contain normal adjuvants such as optical bleaching agents, chemical bleaching agents (peroxides), finishing agents, antistatic agents and the like.

The baths may also advantageously contain a small proportion of water, which facilitates the elimination of hydrophilic dirt; the products according to the invention are most efficient in such cases. When water is present in the dry-cleaning organic solvent, it is advisable to add a small proportion of surfactant to the intensifiers according to the invention, in order to emulsify the water in the solvent. Various ionic or non-ionic surfactants can be used; amine alkyl-aryl-sulphonates are particularly suitable and are 55 widely used in the dry or wet washing of textiles. In such cases it is found that the intensifiers according to the invention cooperate with the surfactants, resulting in considerably improved cleaning.

Although there is no critical maximum proportion of amide to be incorporated according to the invention in the organic solvent used for dry cleaning, a content of 50 g. per litre is usually plenty, and the preferred quantity is usually between approx. 0.1 and 15 g. of intensifier dissolved in each litre of solvent used. More particularly, the proportions of intensifier are lowest in baths containing water. The proportions of surfactants, when used, may be of the same order. The proportion of water the advantage of using which has already been mentioned, preferably does not exceed 100 g./l., the best proportions being 75 between 0 and 20 g./l.

Examples 12 to 15 all show a marked improvement compared with the results of Examples 3, 4 in accordance with the prior art.

Examples 16 and 17

In these examples, the intensifiers were the SIM-1 monosuccinimides of the previous examples, condensed with olefin oxides. For example SIM-OET denotes the succinimide in which each molecule is condensed with 29 mols of ethylene oxide, and SIM-OPR denotes the succinimide condensed with 1.1 mol of propylene oxide per mol of imide.

Washing in perchloroethylene without water in the manner described in the other examples gave the following results:

Ex. No.		Whiteness of—		
		Dirty fabric	Clean fabric	Total
16	SIM-OET (1.45 g.)	36	68.5	104.5
17	SIM-OPR (1.45 g.)	37	76.6	113.6

A comparison with Examples 3 and 4 shows the great improvement resulting from the use of the ethoxylated and propoxylated imides according to the invention. Furthermore, the product SIM-OPR (No. 17) gives better results than the unmodified succinimides SIM-0.8 and 1 in Examples 5 and 7. The total whiteness obtained in the absence of water is equal to that obtained together by SIM-1 succinimide and isopropylamine dodecyl-sulphonate (Example 8).

Example 18

A mono-adipamide of triethylene-tetramine substituted by a C_{28} hydrocarbon radical in its adipic group was used as the intensifier instead of succinimide in tests similar to those in Examples 1 to 8. The results were similar to those given by SIM-0.8.

Examples 19-24

Test washing with trichloroethylene was performed in the same manner as in the preceding examples, using adjuvants comprising some succinimides derived from succinic anhydride substituted with a polybutene or polyisobutene chain. By way of comparison, the test in Example 19 was performed without any adjuvant and Example 20 was performed with the succinimide containing 16 isobutene links already described under the symbol SIM-0.8.

In the other succinimides, the succinic group was substituted by polybutene chains containing "n" (an average number) butene links. The properties of these adjuvants were as follows:

$E-n=17.5$ amines 0.5 mol triethylene-tetramine per mol succinic anhydride

$F-n=8$ amine: tetraethylene-pentamine 0.82 mol per mol anhydride

$G-n=8$ amine: tetraethylene-pentamine 0.82 mol per mol anhydride the amine was also dodecylated

$H-n=8$ amine: similar to F, except that a mixture of C_9-C_{11} carboxylic acids was first fixed on the amine

Each adjuvant was used in the proportion of 1.45 g. per litre of trichloroethylene. The results of the washing operations are shown in the following table.

		Whiteness of—		
		Dirty fabric	Clean fabric	Total
5	Solvent alone	32	64	96
	Solvent plus SIM-0.8	38.7	71.5	110.2
	Solvent plus E	35	65	100
	Solvent plus F	37.4	75.2	112.6
	Solvent plus G	35.5	66	101.5
	Solvent plus H	37.6	68.5	106.1

10 The best result during these tests was given by adjuvant F, i.e. the succinimide having 8 butene links (32 carbon atoms) on the succinic group.

We claim:

15 1. A method for washing solid articles consisting of immersing the articles in a bath consisting of

(a) an organic solvent belonging to the group consisting of hydrocarbon and halo-hydrocarbon dry cleaning liquids, and

20 (b) a monoimide, added to the solvent to a concentration of 0.1 to 50 g. per litre solvent, the monoamide being defined by the formula:

25 where: R is a radical selected from the group consisting of alkyls and alkenyls having 18 to 120 carbon atoms; n is an integer of 0 to 6; (m+p) is 2 to 7; Z and Q are hydrogen.

30 2. A fluid as recited in claim 1, wherein said monoimide is an imide of succinic acid one CH_2 group of which is replaced by a polyisobutene chain having a number of carbon atoms between 18 and 120, and of an amine

35 selected from the group consisting of ethylene-diamine, diethylene-triamine, triethylene-tetramine, tetraethylene-pentamine, pentaethylene-hexamine, pentamethylene-diamine, hexamethylene diamine, tripropylene-tetramine and tetrapropylene-pentamine.

40 3. A fluid as recited in claim 2, wherein said imide has the formula:

45 4. A fluid as recited in claim 2, wherein the final NH_2 group of said imide is blocked by dodecyl-benzene sulfonic acid.

50 5. A fluid as recited in claim 4, wherein said imide has the formula:
